UNITED STATES PATENT OFFICE.

WILLIAM G. MUNN, OF LOUISVILLE, KENTUCKY.

GOLF-TEE MOLD.

Application filed September 20, 1922. Serial No. 589,491.

To all whom it may concern:

Be it known that I, WILLIAM G. MUNN, a citizen of the United States, residing at Louisville, in the county of Jefferson and State of Kentucky, have invented certain new and useful Improvements in Golf-Tee Molds, of which the following is a specification.

This invention relates to golf tee molds, 10 the object of the invention being to provide a simple and inexpensive mold by which a golf player may readily form a sand tee without the necessity of handling the sand with the fingers.

15 In the drawings:

Fig. 1 is a perspective view of my improved mold showing the manner of handling the same in use.

Fig. 2 is a top plan of the mold.

20 Fig. 3 is a side elevation.

Fig. 4 is a view of the blank from which the mold is formed.

In constructing the mold a blank is cut from thin sheet metal of a resilient character, preferably spring brass, in the form shown in Fig. 4, in which the side edges 2 and 3 of the main body portion 1, are shown formed on curved lines struck from the same center, with the end edges of the 30 blanks projecting on lines radial to that center, so that when the blank is rolled to the position shown, with the ends slightly overlapping, it will form substantially a frustum of a cone. The side edge 3 of the 35 blank are formed with a pair of ears 5, which are bent at right angles to the main body, and so disposed as to lie diametrically opposite each other in the completed form of the device.

40 In operation, the mold is grasped by the first joints of the first and second fingers with the smaller end thereof toward the palm of the hand and the fingers against the ears 5. The ball of the thumb is pressed 45 over the smaller end of the mold and the

mold is pressed with a scraping action in the sand until full. The walls of the mold are then slightly contracted by pressure of the fingers to hold the sand tee in the mold, the pressure being relieved after the mold has been placed in position on the teeing off place so that the mold may be lifted from the sand tee. The ball of the thumb leaves a depression in the top of the sand tee to provide a seat for the golf ball.

50 While I have been showing the mold of conical form, which is thought to be the preferable construction, this exact shape may be varied with good results and the ears may be separate pieces soldered to the main body, if desired, and the exact form altered, the purpose of the ears being to form a stop to prevent the mold from slipping through the fingers.

55 I claim:

1. A golf tee mold formed with spring split side walls of conical shape, open at each end, the larger end arranged to receive the material for the tee and the other the thumb of the operator, and a stop at the 70 smaller end, for the purpose specified.

2. A golf tee mold formed with contractible and expandible side walls open at each end, one end arranged to receive the material forming the tee and the other end to 75 receive the ball of the player's thumb, and oppositely-arranged lateral projections formed on the latter end to receive the player's fingers.

3. A golf tee mold formed with split side 80 walls open at each end of conical shape, the large end arranged to receive the material forming the tee and the small end to receive the ball of the player's thumb, and oppositely-arranged projections extending from 85 the small end, for the purpose specified.

In testimony whereof, I have hereunto set my hand this 9th day of September, 1922.

WILLIAM G. MUNN.
